(57) **CLAIM**

The ornamental design for an audio speaker horn, as shown and described.

DESCRIPTION

FIG. 1 is a top perspective view of an audio speaker horn, showing my new design;

FIG. 2 is a bottom perspective view thereof;

FIG. 3 is a front elevation view thereof, the rear, left, and right side elevation views being the same;

FIG. 4 is a top plan view thereof; and,

FIG. 5 is a bottom plan view thereof.

The broken lines in the figures illustrate the portions of the audio speaker horn and form no part of the claimed design.
